UNITED STATES PATENT OFFICE

LAWRENCE H. MORSE, OF CLEVELAND, OHIO, ASSIGNOR TO THE AMERICAN MULTIGRAPH COMPANY, OF CLEVELAND, OHIO, A CORPORATION OF OHIO

DEVICE FOR LOADING TYPE

Application filed May 13, 1929. Serial No. 362,519.

This invention relates to a machine for conveniently loading type into line holders. The invention is concerned particularly with handling short type, grooved on its opposite sides, suitable for use on the printing machine known as the multigraph. When such type is supplied to users, it is customary to employ a slotted tube as a holder, each tube being adapted to carry a convenient number 5 of type of the same character, held in a row in a slot along the tube. The primary object of this invention is to provide mechanism for efficiently loading the type into such tubes one after another suitable for delivery. 10 My invention also comprises the feature of mounting the loading device as an attachment on a type casting machine so that the type as discharged by the casting machine are automatically carried to the tubes and loaded 15 therein. A further object of the invention is to insure a definite number of type being in each tube. 20 Another object of this invention is to lock automatically the ends of the tubes to prevent 25 the removal of type therefrom until such time as it is desired to discharge type into a suitable machine. The tubes into which my machine sets the type are preferably provided with tongues cut out of the metal of the tube 30 itself and adapted to be pressed inwardly to prevent the escape of type from either end of the tube. My mechanism automatically presses these tongues into the locking position. My mechanism also insures the tongue 35 at the receiving end of the tube being in non-locking position when a tube is about to be loaded. This enables old tubes in which the tongues may have become displaced to be used in the machine without preliminary 40 treatment. Other features of the invention will become apparent from the following detailed description of the embodiment shown in the drawings.

In the drawings, Fig. 1 is a side elevation 45 of my loading device in the position it occupies when attached to a frame of a type casting machine, the outline of the adjacent portion of such frame being indicated by broken lines; Fig. 2 is a longitudinal axial section of the loading mechanism in a plane

at right angles to Fig. 1; Figs. 3 and 4 are vertical sections through the upper portion of the loading mechanism on planes indicated by the lines 3—3 and 4—4 on Fig. 2; Fig. 5 is a detail in vertical section illustrating the 55 upper end of a type receiving tube and the tongue-straightening plunger which coats therewith; Figs. 6 and 7 are cross sections of the plunger and tube on the correspondingly numbered lines in Fig. 5; Fig. 8 is a 60 transverse section through the loading apparatus substantially in the plane indicated by the line 8—8 in Fig. 1; Fig. 9 is a detail of gearing operating the type counting 65 device of the loading mechanism, being a 65 vertical section on a plane indicated by the line 9—9 on Fig. 8; Fig. 10 is an enlarged cross section through the tube-straightening plunger and adjacent parts as indicated by the line 10—10 on Fig. 4; Fig. 11 is an elevation 70 of a peripheral portion of the type counting wheel, associated with a row of type; Fig. 12 is a perspective of one of the type 75 with which the counting wheel of Fig. 11 is designed to cooperate; Fig. 13 is a transverse section through the indexing mechanism as indicated by the line 13—13 on Fig. 1; Fig. 14 is a longitudinal section through the mechanism for closing the upper locking 80 tongue of the type tube, the plane of this section being indicated by the line 14—14 on Fig. 8; Fig. 15 is a longitudinal section at the lower end of the tube carrier, illustrating the 85 position of a tube as it is being put into place in the carrier.

The temporary type holders which the specific embodiment shown is designed to load comprise thin metal tubes having only sufficient gauge of stock to enable them to form effective carriers for shipping the type and retaining it until it is desired to place it in the type case. These tubes are illustrated at D in Figs. 1, 2, 4—7, 14 and 15. The tube has a straight longitudinal slot d from end to end; the back portion of the tube, diametrically opposite the slot, is flattened as shown at d'. The distance across the slot d is slightly greater than the distance across the neck c of the type C shown in Fig. 12, so that these edge portions of the tube are adapted to 95 100

cupy the grooves of the type with the head of the type c^1 exterior of the tube and the foot of the type c^2 freely occupying the interior.

To prevent escape of the type from the tube, I form on the flattened back of the tube a pair of tongues d^2 and d^3 . These tongues are made by cutting out a portion of the back and bending it inwardly as illustrated in Figs. 5 and 7. When in the position there shown, they are adapted to engage the foot of any type carried by the tube and preventing it passing out at either ends. The tube described forms a convenient holder for a row of type. The loading mechanism is designed to feed a definite number of type, all of the same character, onto such tube and to bend inwardly the retaining tongues d^2 and d^3 . Such loaded tube is then ready for the market, and the purchaser is enabled to transfer the type into his type case by simply pressing back one of the tongues and shoving the type out of the tube or allowing it to drop, according to the circumstances.

The mechanism of this invention is designed to have a number of the split-tube holders placed in it manually; to load each holder with definite number of type, and to press inwardly the tongues of the holder to retain the type therein.

Fig. 1 indicates by the broken line A, the frame of a type casting machine on which my loading mechanism may be mounted as an attachment. The frame of the loading mechanism is a yoke 10 which may be bolted to the casting machine in a vertical plane but in the inclined position shown to such figure. A suitable type guide B (which may comprise a pair of spaced parallel bars) leads from the casting machine to my loading mechanism.

The loading mechanism is preferably timed in relation to the casting machine, and to this end I find it convenient to couple the main driving shaft 20 of the attachment directly to a shaft of the casting machine with which my shaft perfectly aligns. This shaft 20 is shown as mounted by a suitable bearing at the upper portion 11 of the yoke 10. It is thus driven at its right hand end in Fig. 2, the left hand end being shown as equipped with a hand wheel 21 by which the mechanism may be turned over by hand for testing.

The yoke 10 carries two longitudinally aligned bearings 31 and 32 mounted in the upper portion 11 and the lower portion 12 of the yoke. In these bearings is journalled a longitudinal shaft 30 on which are mounted upper and lower disk-like heads 35 and 36. The upper head 35 is pinned or otherwise secured tightly to the shaft 30, the lower head is adjustable along the shaft, as hereinafter explained, but in operation is rigid with it. The shaft 30 with these heads constitutes a skeleton drum which may carry a large num-

ber of tube holders of the character described, and may be rotated step by step to present one tube after another to the mechanism receiving type through the guide B from the casting machine, whereby such holders may be loaded. 70

To hold the tubes D in the rotary carrier described, I provide a series of equi-distant spring clips 50 and 51 arranged on the heads 35 and 36. These clips are spring stirrups adapted to engage the sides of the tubes and hold them in place, as indicated particularly in Figs. 13. The tubes are positioned by engaging notches 52 and 53 in the heads. 75

Carried by the yoke-frame beneath the lower head 36 is a disk 60 having an up-standing flange 61 so positioned that it may freely engage the front or slotted portion of the tubes, when these tubes are in position in the clips of the heads as shown in Fig. 2. The disk 60 is movable up and down for adjustment, but in operation is stationary. To place a tube in the carrier, it is first put in an inclined position with the lower end inside of the flange 61 as shown in Fig. 15, and is thereupon swung into position parallel with the shaft 30 so that it enters the corresponding clips 50 and 51 and is retained in place. In this movement a suitable tongue 55 secured to the lower end of the head 36 engages the retaining tongue d^3 of the tube and forces it inwardly if it is not already in that position, thus blocking the discharge from the tube at that end. Accordingly, the mere act of placing the tubes in the mechanism 100 closes the lower tongues. 95

To rotate the tube carrier, comprising the shaft 30 and heads 35 and 36, I provide the cam-operated indexing mechanism shown in Figs. 1, 2 and 13, which I will now describe. 105 Rigid on the shaft 30 is a notched wheel 70 (shown as fastened by a screw to the head 35). Cooperating with the notches of this disk wheel on a detent pawl 71 (Fig. 13) and a feeding pawl 72. The feeding pawl is pivoted to an operating arm 73 journalled on the exterior of the bearing 31. A spring 74 connected to the pawl and arm tends to keep the pawl in its operative position. The other detent pawl is pivoted at 75 to the yoke and has an extension 76 to which is attached a tension spring 77. The arm 73 carrying the feeding pawl is formed with a cam portion 78 which is designed to coat with a roller 79 on the detent pawl. 115 120

When the cam arm 73 is swung in the clockwise direction from the position shown in Fig. 13, the cam engages the roller 79 and withdraws the detent pawl from the notched wheel 70. In this movement the feeding pawl withdraws from the notch and slides idly over the top of the adjacent tooth and drops into the preceding notch; then as the cam plate 73 is swinging a short distance in the opposite direction, the feeding pawl 125 130

turns the notched wheel 70 until the cam portion of the arm clears the roller 79, whereupon the detent pawl springs back into active position and engages in the next notch presented. The rotation is thus step-by-step, a tooth at a time. The spacing of these teeth corresponds to the spacing of the clips on the tube carrier, and accordingly each complete forward and backward stroke of the cam arm operates to present a fresh tube to the active position and to withdraw a filled tube therefrom.

The mechanism for giving the described movement to the cam arm comprises a link 80 leading from the cam arm to a bell crank 81 (Fig. 1) which is pivoted at 82 to the yoke and carries a pair of cam rollers 83 and 84. These rollers coact respectively with cams 85 and 86 on the main shaft 20. The cams act in a complementary manner on the two rollers, the cam 85 forcing the rock shaft toward the left (Fig. 1) while the cam face 86 recedes to allow it, and thereafter the cam 86 forcing the roller 84 to the right or upwardly while the receding face of the cam 85 allows this movement. The cams 85 and 86 may really be one integral member pinned to the shaft 20 as illustrated in Fig. 2.

It will thus be seen, each complete rotation of the shaft 20 is accompanied by an angular movement of the tube-carrier a distance corresponding to the spacing of the successive tubes. The tubes are placed manually in the side of the carrier which is visible in Fig. 1. The speed of the carrier is such that there is no difficulty in keeping it continuously supplied with tubes. When the tube comes into the extreme right hand position, it is thereby properly aligned with the type guide above it so that it may receive type, as will now be explained.

Immediately following the described action of bringing a tube into alignment with the guide from the supply, an action takes place to move such tube longitudinally toward the guide (that is, diagonally upwardly in this embodiment) to make a close connection with the guide. This is effected by mechanism shown in Figs. 1, 2 and 3 and will now be described.

On the shaft 20 are a pair of cams 100, 101 (shown as an integral unit) which act in complementary manner on the rollers 102 and 103 on the bell crank 104 rigid on a shaft 105, journaled in the upper end of the yoke portion 11. Such mechanism rocks the bell crank first in one direction and then in the other. This bell crank has a curved extension 107 which engages a roller 110 on the bell crank 111 pivoted at 112 to the yoke and connected at its other end to a link 113. This link, at the opposite end, is connected with an intermediately pivoted lever 114 at the lower end of the yoke frame. The other end 65 of this lever is connected by a link 115 with

a plunger 116 directly beneath the type tube which is in load-receiving alignment. The result is that after the type tube has been brought into registration it is shoved upwardly to make the desired closed connection with the type guide, and thereafter the plunger is withdrawn.

The link 113 is adjustable in length as by having a portion of it 117 screw threaded into another portion. However, as the tubes 75 may not be accurately of the same length, the link is also made elastic to prevent injuring tubes which may be too long. This is effected by making the link of two aligned separated rods one of which is providing a 80 sleeve 118 which has a limited slidable connection with the other rod, and placing within the sleeve a compression spring 119 abutting the ends of the two members.

As the tubes D used in my machine may be 85 old tubes, it may result that when the tube is placed in the machine the upper tongue d^2 may stand projecting into the tube into position to interfere with the loading of the tube. Accordingly, I provide mechanism 90 which operates before the type enter the tube to press back any tongues so projecting and thus leave the tube free to receive the type. This mechanism, which operates downwardly on the tube while the plunger 116 holds it in 95 raised type-receiving position, will now be described.

As the type delivered from the casting machine come down the guide B they are guided between a pair of spaced bars 90 forming a 100 continuation of the guide B. These bars are shown as secured to a plate 91 on the right hand side of the yoke portion 11. The edges of bars on opposite sides of the slot enter the grooves of the type, while the feet of the 105 type occupy a recess behind the slot. In this recess is a plunger 130 (Figs. 4, 5, 8 and 10), slidably guided between the frame plate 91 and the guide bars 90, and connected by a link 131 to a rock arm 132 on the rock 110 shaft 105.

The result of the described mechanism is that at the same time that the linkage system heretofore described is operated to shove up the plunger 116, the plunger 130 is shoved 115 downwardly, and as the tube is held at this time by the plunger 116, the plunger 130 forces back the tongue d^2 into the position shown in broken lines in Fig. 5. The lower end of the plunger 130 is reduced and beveled 120 as shown at 135 in Fig. 5 to effect readily this operation. The plunger 130 is intermediately cut out as shown at 137 to enable the type counting wheel, about to be described, to act on the type.

To insure a definite number of type entering each tubular holder, I provide a counting device which acts on the type as they travel down the guide bars 90 from the receiving guide B to the positioned type tube 130

D. This counting device is so geared and driven that it causes the passage of a fixed number of type for each receiving tube brought into position.

5 The counting device above mentioned includes a notched wheel 140 extending through the opening 137 in the plunger 130 and engaging the type C in the guiding slot 90. Each notch of the wheel may feed only 10 a definite number of type, as for instance one, two or three type and the wheel is positively driven in timed relation with the step-by-step feed of the tube carrier. Accordingly, the passage of a definite number of 15 type to each tube is effected.

In the specific embodiment shown, the type have beveled feet c^2 , and the notches 141 of the counting wheel are formed to correspond to the bevels of two adjacent type, as illustrated in Fig. 11. Accordingly, if it is desired to load for instance fifty type into the tube, there will be twenty-five notches on the periphery of the counting wheel.

The counting wheel 140 is rigidly mounted 25 on a shaft 142 journaled in bearings in the yoke portion 11. This shaft carries a pinion 145 which may mesh periodically with a segmental gear 146 rigid with the shaft 20. Also rigid on this shaft 20 is a cam 147 30 having an arcuate portion adapted to register with a correspondingly concaved edge in a collar 148 rigid on a shaft 142, as shown in Figs. 2 and 8. The gear 146 is shown as pinned to the cam 147, and the cam 147 as 35 having a lug engaging a collar 149 pinned to the shaft 20.

It will be seen from the construction just described, that when the arcuate face of the cam 147 is rotated past the collar 148, the 40 shaft 142 and hence the counting wheel 140 is locked stationary. When however the arcuate cam clears the collar 148, the teeth on the gear 146 come into mesh with the teeth on the pinion 145 and cause that pinion to 45 rotate, thus rotating the counting wheel.

By properly selecting the gearing 145, 143, the counting wheel may cause as many teeth as desired to pass a given point for one rotation of the shaft 20, and thus feed as many 50 type as desired to the receiving tube. I have found that fifty type in a tube is a convenient number and that it is convenient to provide twenty-five teeth on the wheel 140 (the wheel feeding two teeth at a time) and 55 arrange the gearing so that the wheel makes a complete rotation for each rotation of the shaft 20, but this ratio may be varied as may be desired. This may be readily effected (after the collar 149 and the driving coupling to the shaft 20 have been removed) by 60 removing the cam 147 and gear 146 from that shaft and removing the collar 148 and pinion 145 from the shaft 142, then substituting parts having different ratios for those 65 moved.

As the type are fed by the counting wheel they pass downwardly along the guideway provided by the bars 90 into the upper end of the aligned tube D. After such tube has been loaded, it is desirable to press inwardly the tongue d^2 to lock that end of the tube. This is effected by a bell crank 150 which has a nose adapted to shove against the tongue d^2 as illustrated in Fig. 14. The other arm of this bell crank is connected by a link 151 75 to the rock arm 132 rigid on the shaft 105, which operates the positioning and tongue-straightening plungers heretofore described.

It will be seen however from the plane of Fig. 14 as indicated in Fig. 8, that the pusher 150 acts on a tube one in advance of the tube acted on by the plungers. Accordingly, while the plunger 116 is shoving upwardly a fresh tube to position it to receive a line of type, the bell crank pusher 150 is acting on the 85 tube just loaded to close the tongue d^2 thereof. Following the closing action the loaded tube remains in the carrier until, in the step-by-step rotation of the carrier, such tube comes into engagement with a bracket 127 (Fig. 90 18) which forces the loaded tube out of the carrier and it falls into a suitable receptacle.

As the individual type with which this machine operates are very light, it is desirable to provide means to prevent a type 95 sticking in the channel between the counting wheel to the receiving tube. Ordinarily the weight of the type is sufficient to feed them, but if there should be only one or two type in the channel, and particularly if there 100 should happen to be a little dirt on such type, they might fail to reach the tube and thus the tube be delivered without the full number of type therein. To overcome this occasional disadvantage, I provide for delivering a jet of air against the type just as it 105 leaves the counting wheel, and I find this to be effective in overcoming the difficulty.

The mechanism for delivering the air jet above described as illustrated in Fig. 1, comprises a cylinder 160 pivoted at 161 to the frame of the casting machine. In this cylinder is a plunger 162 to which is connected a rod 163 terminating in a strap surrounding an eccentric 164 on a shaft 165 which is preferably one of the shafts of the type casting machine. From the lower portion of the cylinder 160 a tube 167 leads to the vicinity of the type, where they are engaged by the counting wheel, and has a nozzle discharging 115 downwardly directly against such type.

It is desirable to make the machine adjustable for different lengths of tube, in case more than one standard length is employed. I have shown means for adjusting it for two lengths, one being shorter than the standard shown in the drawing. Means for effecting this is illustrated in Figs. 1 and 2 and will 125 now be described.

The lower head 36 of the type carried in- 130

stead of being secured directly to the shaft, as in the case of the upper head 35, is slidably mounted on the shaft but has secured rigidly of itself two studs 170 on opposite sides of the shaft, which studs pass through a block 171 rigidly secured by the pin 172 to the shaft. Suitable pins 173 normally rigidly lock the studs 170 in the block 171, and thus rigidly secure the head to the shaft, but the removal of these pins 173 enables the head to be raised, after which the pins may be located in other holes in the standards. I have shown such relocating holes at 174.

Similarly, the stationary disk 60 has secured to its studs 62 which extend slidably into the lower portion 12 of the yoke frame and are normally held rigidly thereto by pins 63. The removal of these pins enables the disk to be raised, after which the pins may be relocated in other holes, as indicated at 64. This allows the disk to be raised correspondingly to the raising of the head 36. A longer plunger will then be substituted for the plunger 116 shown in the drawings and then the machine will be ready for receiving tubes of the shorter standard.

It is to be understood, from the description of the embodiment shown in the drawings, that my attachment may be secured to a type casting machine or otherwise as desired; that it operates automatically to position tubes, manually placed in the device, and effectively holds them in registration with the type delivery channel, and that the mere act of putting the tube in the carrier automatically closes the lower tongue on the tube. The machine opens the upper tongue (if it was not already in open position), and then to insure a definite number of type entering the tube, after which the upper tongue is closed and the loaded tube delivered ready for shipping. The carrier is equipped for receiving a sufficient number of tubes to enable the machine to operate rapidly while still allowing ample time for the manual placing of the tubes. I have found it very satisfactory to couple my loading device directly to a type casting machine and operate it at a speed to receive the type as cast; but, obviously, the machine could operate independently of a casting machine, receiving its type from any suitable source.

I claim:—

1. In a machine of the character described, the combination, with mechanism for guiding type in a row, of mechanism for automatically causing such row to register with a succession of independently removable tubular type holders one after the other, whereby type may be transferred from the guide to the type holders.

2. The combination with a guide for a row of type, of mechanism adapted to carry a plurality of independent removable type holders, means for bringing such holders

one after the other into registration with the guide, and mechanism for feeding type from the guide to the holders.

3. The combination with a type guide, of a movable carrier having means thereon adapted to receive and temporarily hold a plurality of individually removable type holders, means for giving said carrier a step-by-step movement to present the type holders one after the other to the guide, and mechanism for feeding type from the guide to the holders. 70 75

4. The combination with a type guide, of a rotary carrier, means on the carrier for holding individual removable type holders, means for giving the carrier a step-by-step rotation to present the holders successively to the guide, and mechanism for feeding type from the guide to the holders. 80

5. The combination with a type guide, of a rotary shaft, a pair of heads thereon, clips on the heads adapted to hold removable type holders parallel with the shaft, means for giving the shaft a step-by-step rotation to present the type holders successively to the guide, 85 90 and mechanism for feeding type from the guide to the holders.

6. The combination with a type guide, of means for positioning a type holder in registration therewith, and means for automatically causing the passage of a plurality of type from the guide to the holder and means for so controlling such passage that a definite number of type shall enter the holder. 95

7. The combination of a type guide, a tubular type holder adapted to be held in registration therewith to receive type therefrom, and a counting device movable with the passage of type from the guide toward the holder to regulate the number of type entering the 100 105 holder.

8. The combination of a type guide, a type holder, means for positioning it in registration with the guide, and a rotary counting wheel coacting with the type as fed toward the holder and adapted to control the total 110 number of type entering the holder.

9. The combination with a type guide, a carrier adapted to hold a plurality of temporary type holders, means for moving the carrier step-by-step to present the holders to the guide successively, a counting device coacting with the type, and mechanism for moving said device in timed relation with the mechanism for moving the carrier. 115 120

10. The combination with a type guide, a type holder adapted to register therewith and receive type therefrom, mechanism for presenting the holder to the guide, a wheel coacting with the type moving in the guide toward the holder, and mechanism for driving said wheel in timed relation with the mechanism for positioning the holder, whereby a definite number of type enter the holder. 125

11. The combination of a type guide, 130

- means for holding a set of temporary type 5
holders, means for causing them to register
successively with the guide and receive type
therefrom, a toothed-wheel engaging the
type in the guide, means for rotating the
wheel in the direction to have its engaging
face moved toward the holder. 70
12. The combination of means for holding
a temporary type holder, means for feeding
10 type thereinto, and means for thereafter clos-
ing the receiving end of the holder. 75
13. The combination with a type holder
having a locking tongue, means for feeding
15 type into the holder, and means for thereaf-
ter moving the tongue across the type to lock
the type into the holder. 80
14. The combination of a temporary type
holder comprising a tube having a slot parallel
20 with its axis and a tongue cut out from the
base of the tube opposite the slot and adapted
to project into the tube, means for loading
such tube with type, and means for thereafter
pressing the tongue into the tube to prevent
25 the type passing out that end of the tube. 85
15. The combination, with a type guide, of
a carrier for a temporary type holder
equipped with a locking device, means for
30 moving the carrier to present the temporary
holder to the type guide, and means operat-
ing automatically to close the distant end of
the type holder placed in the carrier. 90
16. The combination of a type guide, a car-
rier for a plurality of type holders, means
35 for moving the carrier step-by-step to present
successive holders to the guide, and means
whereby the placing of a type holder in the
carrier automatically closes the type holder
in a region distant from the guide. 95
17. The combination of a type guide, a
40 rotary carrier adapted to hold a plurality of
tubular type holders, means for giving the
carrier a step-by-step rotation to present such
holders to the guide successively, and means
operating consequent upon the insertion of
45 the type holder in the carrier for closing the
end of the type holder a distance from the
guide. 100
18. The combination with a type guide, of
means for presenting thereto a type holder
50 equipped with a locking tongue, means for
forcing said tongue out of the way to enable
type to enter the holder. 110
19. The combination of a type holder com-
55 prising a tube having a longitudinal slot and
having a tongue cut out from the tube oppo-
site the slot and adapted to project into the
tube to prevent discharge therefrom, means for
guiding a row of type, means for present-
60 ing the tubular holder to the type guide, and
automatic means for forcing back the tongue
to free the admission to the tubular holder
from the guide. 115
20. The combination of a type guide, a
65 movable type carrier adapted to hold a plu-
rality of individual typeholders, means for
moving the type carrier step-by-step to pre-
sent successive type holders to the type
guide, and means for automatically moving
70 to idle position a locking device on the type
holder. 120
21. The combination of a type guide, means
for positioning a temporary type holder in
registration therewith, means for automatically
moving to idle position a locking device
75 on the type holder, and means acting after
the type holder is loaded for forcing the lock-
ing device into active position. 125
22. The combination with a type guide,
means for moving a removable temporary
80 type holder laterally into alignment with the
guide, such means for moving an aligned
holder longitudinally into close connection
with the guide. 130
23. The combination with a type guide, a
movable type carrier adapted to hold remov-
85 able parallel type holders, means for moving
the carrier step-by-step to present suc-
cessive holders to the guide, and means for
moving each presented holder longitudinally
90 thereof to form a close connection with the
guide. 135
24. The combination with a type guide, a
rotary shaft, a pair of heads thereon each
equipped with an annular set of clips, the
95 clips in the two heads aligning whereby they
may hold temporary type holders parallel
with the shaft, means for giving said shaft
a step-by-step rotation to bring one type
holder after another into alignment with the
100 guide and means for moving any aligned
type holder toward the guide. 140
25. The combination with a type guide,
means for moving type holders laterally into
registration with the guide, means for moving
105 any holder in registration longitudinally
toward the guide and holding it in that po-
sition, and means acting on the portion of the
type holder adjacent the guide for forcing
back a locking device thereon while said
holding means is active. 145
26. The combination with a type guide, of
a movable type carrier equipped to hold a
110 plurality of parallel type holders, means for
moving the carrier to present successive hold-
ers to the guide, and means for adjusting the
carrier to enable it to carry holders of dif-
ferent length. 150
27. The combination of means for guiding
type, of a rotary carrier, two sets of devices
115 on the carrier for engaging temporary type
holders parallel with the axis of rotation ad-
jacent each end of the type holder respec-
tively, and means for moving one set of said
devices longitudinally of the axis of rota-
120 tion to enable the carrier to coact with holders
of different length. 155
28. The combination of a type guide down
which type may pass by gravity, a rotary
125 holder having means for carrying a plu-
rality of temporary tubular type holders en- 160

gaged near their upper and lower ends, means for moving said carrier step-by-step to present the upper ends of the type holder successively to the guide, and means whereby the part of the carrier which engages the lower portion of the holders may be adjusted up and down on the axis.

29. The combination of a type guide, of a rotary shaft, a pair of heads on the shaft, 10 equa-distant clips on the respective heads adapted to hold tubular type holders parallel with the shaft, each head being rotatable with the shaft and the head which is more distant from the guide being adjustable longitudinally of the shaft.

30. The combination of a type guide, of a rotary shaft, a pair of heads on the shaft adapted to hold temporary type holders, each head being rotatable with the shaft and the 20 head which is more distant from the guide being adjustable longitudinally of the shaft, a disk-like member beyond the latter head adapted to be engaged by the ends of type holders mounted on the carrier, and means 25 for holding said disk-like member stationary while allowing for its adjustment lengthwise of the shaft.

31. The combination with a type guide, means for holding a plurality of temporary 30 type holders, means for moving the holding means to successively present a temporary type holder to the type guide, and there being provisions for causing the type to pass normally from the guide into the holder, and 35 additional propelling means acting against the type in the guide to prevent its clogging therein.

32. The combination with a type guide down which type may pass by gravity, a type 40 holder, means for holding it below the guide in registration therewith and means for delivering an air blast against type in the guide to prevent the type clogging therein.

33. The combination of a type guide, a temporary type holder, means for holding the type holder in registration with the guide, means for feeding the type along the guide and counting them as they are fed, and propelling means acting against the type in the 50 guide between the region where they are counted and the entrance to the type holder.

34. The combination of a type guide down which type may pass by gravity, a carrier, means for mounting therein a plurality of 55 type holders, means for moving the carrier step-by-step to present successive type holders to the guide, and means for delivering an air blast against the type in the guide tending to urge them toward an aligned type holder.

35. The combination with a type guide along which type may be fed, of a rotary carrier equipped with means for holding individual type holders arranged parallel with 60 the axis of rotation, a drive shaft, a cam

mechanism thereon, and lever mechanism operated thereby for rotating the carrier step-by-step to present one holder after another to the guide.

36. The combination with a type guide 70 along which type may be fed, of a rotary carrier equipped with means for frictionally holding individual tubular type holders arranged parallel with the axis of rotation, means for rotating the carrier step-by-step 75 to present one holder after another to the guide, the cam mechanism, and lever mechanism operated by such cam mechanism for forcing any positioned temporary type holder toward the guide.

37. The combination with a type guide along which type may be fed, of a rotary carrier equipped with clips for frictionally holding individual tubular type holders arranged parallel with the axis of rotation, mechanism 85 for rotating the carrier step-by-step to present one holder after another to the guide, mechanism for moving longitudinally any positioned type holder toward the guide, mechanism for forcing to idle position a locking tongue on the type holder, near its entrance, and mechanism acting thereafter for forcing said locking tongue to active position.

38. The combination of a type guide, mechanism for positioning a type holder in registration therewith, a controlling device for causing a definite number of type to pass from the guide to the holder, said controlling device comprising a wheel adapted to engage the type, a pinion rigid therewith and a mutilated gear for giving the wheel interrupted rotations, said gear operating in timed relation with the first mentioned mechanism.

39. The combination of a type guide, means 105 for positioning a type holder in registration therewith, a controlling device for causing a definite number of type to pass from the guide to the holder, said controlling device comprising a toothed wheel, a shaft therefor, 110 a pinion on the shaft, a driving shaft, and a mutilated gear on the driving shaft for giving the toothed wheel shaft interrupted rotation.

40. The combination of a type guide, means 115 for positioning a type holder in registration therewith, a controlling device for causing a definite number of type to pass from the guide to the holder, said controlling device comprising a wheel, a shaft therefor, a pinion 120 on the shaft, a driving shaft, a mutilated gear on the driving shaft for giving the wheel-shaft interrupted rotation, and interlock members on the driving shaft and wheel shaft for preventing the rotation of the latter shaft 125 at a time when the mutilated gear is out of mesh with the pinion.

41. The combination with a tubular type holder having a tongue adapted to be projected inwardly to prevent discharge of type 130

- from the holder, a type guide, means for positioning the holder in registration with the guide and means for forcing said tongue inwardly to prevent discharge of the type in 5 the opposite end from that adapted to receive type from the guide. 79
42. The combination with a type guide, a movable carrier having devices for carrying a plurality of temporary tubular type holders, means for giving said carrier a step by 10 step movement to bring one type holder after another into alignment with the guide, and means for moving each aligned holder longitudinally toward the guide. 75
43. The combination with a type guide down which type may pass by gravity, a controlling device engaging the type and driven to control the passage of a definite 15 number of type, a carrier adapted to hold temporary type holders, means for moving the carrier to present holders successively to the guide, an automatically acting air 20 pump and means for delivering the discharge thereof against type in the guide in the region between the controlling device and the type 25 holder. 80
44. The combination with a type guide along which type may be fed, of a rotary carrier equipped with means for holding individual 30 tubular type holders arranged parallel with the axis of rotation, a drive shaft, a cam mechanism thereon, lever mechanism operated thereby for rotating the carrier step-by-step to present one holder after another 35 to the guide, another cam mechanism, and lever mechanism operated by the latter cam mechanism for forcing any positioned temporary type holder toward the guide. 90
45. The combination with means for producing individual type grooved on its opposite sides, a series of type holders arranged 40 in a circuit on a carrier and having edges adapted to enter said grooves, means for moving the carrier to successively present a type holder to loading position, and means for causing a type to enter the holder at such 45 position. 100
46. The combination of a rotary carrier, a set of individual type holders carried there-by and arranged about the axis of the carrier, 50 means for casting type, and automatically acting mechanism for loading such type into the type holders. 110
47. The combination with a type casting machine, of a rotary drum carrying a plurality of type holders, and means driven in 55 timed relationship with the typecasting machine for turning said drum about its axis to bring one type holder after another into coaction with the casting machine to receive the product thereof. 115
48. The combination with mechanism for casting individual type grooved on its opposite sides, of a rotary drum having longitudinal type channels with restrictive edges 60
- parallel with the axis of the drum, means for rotating said drum, means for loading type from the type casting machine onto different channels of the drum as presented, both of said means being operated by the typecasting machine. 79
49. The combination with a type casting machine, of a movable type carrier adapted to hold parallel type holders, and means driven in timed relationship with the typecasting machine for moving the carrier to present successive holders to the casting machine. 75
50. The combination with a type casting machine adapted to produce short individual type grooved on its opposite sides, of a movable carrier having means thereon adapted to receive and temporarily hold a plurality of removable type holders each having parallel edges adapted to occupy the grooves of such type, and means driven in timed relationship with the typecasting machine for moving said carrier to present such type holders one after the other to the casting machine. 85
51. The combination with a type casting machine, of rotary member equipped with means for holding type holders parallel with the axis of the member, and means driven in timed relationship with the typecasting machine for rotating said member to bring one type holder after another into coaction with the casting machine. 90
52. The combination, with means for producing type, of a rotary carrier, a set of individual removable type holders on the carrier, means for rotating the carrier to present the holders successively to a guide leading from the producing device, and means for automatically transferring type from the guide to any presented holder. 100
53. In a machine of the character described, the combination, with mechanism for guiding type from a typecasting machine, of mechanism driven in timed relationship with the typecasting machine for automatically causing such guide to register with a succession of individually removable type holders one after the other, whereby type may be transferred from the guide to different type holders. 110
54. In a machine for loading type, the combination with a type guide from a typecasting machine, a plurality of independent removable type holders carried in the machine at one time, and means driven in timed relationship with the typecasting machine for bringing such holders one after the other into registration with the guide. 115
55. The combination of a rotary carrier, means on the carrier for holding individual removable type holders, means for turning the carrier about its axis, and means for releasing a holder from the carrier. 125
56. In a machine of the character described, the combination of a rotary carrier, 130

a set of longitudinal individually removable type holders arranged parallel with each other about the axis of the carrier and each adapted to receive a row of type, means for 5 rotating the carrier to present the holders successively, and means for ejecting a holder from the carrier.

57. The combination of a rotary member, 10 clips therein adapted to hold removable type holders, a device for ejecting holders, and means for turning the member about its axis to present the type holders successively to the ejecting device.

In testimony whereof, I hereunto affix my
15 signature.

LAWRENCE H. MORSE.
